Primary Examiner — Elizabeth A. Albert(74) *Attorney, Agent, or Firm* — Stetina Brunda Garred and Brucker(57) **CLAIM**

The ornamental design for a writing instrument, as shown and described.

DESCRIPTION

FIG. 1 is an elevated perspective view of the writing instrument of the present invention; FIG. 2 is a top view thereof;

FIG. 3 is a right-side view thereof;

FIG. 4 is a left-side view thereof;

FIG. 5 is a bottom view thereof;

FIG. 6 is a view of the proximal end thereof; and,

FIG. 7 is a view of the distal end thereof.

The broken lines in the drawings are included to show portions of the writing instrument that form no part of the claimed design.

1 Claim, 3 Drawing Sheets(56)
